TRANSFER MEANS FOR REGISTERING
WRAPPERS AND BANDS

Alfred W. Kath, Detroit, Mich., assignor to Arthur Colton Company, Detroit, Mich., a corporation of Michigan

Application March 1, 1934, Serial No. 713,587

11 Claims. (Cl. 93—2)

The invention relates to machines for banding and wrapping cigars of that type in which the wrapper and the band are first placed in proper registration with each other and the cigar, and are then simultaneously engaged with the wrapping mechanism. With machines of this type it is necessary to provide

First, mechanism for forming the wrapper including means for cutting off the wrapper from a continuous strip and varying the length to correspond to the particular cigar to be wrapped;

Second, means for feeding the bands from a stack and delivering one band in proper registration with each wrapper;

Third, means for feeding the cigars so as to deliver the same successively to the wrapping mechanism;

Fourth, means for properly registering the wrapper and band with the cigar to be wrapped,

and

Fifth, wrapping mechanism for simultaneously wrapping the wrapper and band about the cigar.

It has been found difficult to arrange these several mechanisms in the machine so as not to interfere with each other, and therefore it is desirable to separate the same. This, however, necessitates transfer mechanisms by the operation of which the several elements of the final product are taken from their different locations and delivered in proper registration with each other. Thus the band must be transferred into registration with the wrapper, the wrapper and band transferred into registration with the cigar, and cigar, band and wrapper transferred into registration with the wrapping mechanism.

The separate transfer of the wrapper and of the band may be easily accomplished by the use of suction heads. When, however, the band and wrapper are placed in registration and must together be transferred into registration with the cigar, the problem is more difficult. This is for the reason that if the suction head contacts with the wrapper it is cut off from contact with the band so that there is no certainty that the latter will be carried with the former. This difficulty I have overcome by a peculiar construction of transfer mechanism which forms the subject matter of the present application for patent, as more fully hereinafter set forth.

In the drawings:

Fig. 1 is a plan view of the machine;

Fig. 2 is a similar view with some of the mechanism removed and showing parts in the different positions of adjustment;

Fig. 3 is a cross section on line 3—3 of Fig. 1; Fig. 4 is a section on line 4—4 of Fig. 1;

Fig. 5 is a bottom plan view of the transfer carrier shown in Fig. 4;

Fig. 6 is a section on line 6—6 of Fig. 7.

Fig. 7 is a plan view partly in horizontal section showing the transfer carrier and resilient guiding means for the cigar;

Fig. 8 is a section on line 8—8 of Fig. 7;

Fig. 9 is an end elevation viewed from the right, Figs. 7 and 8;

Fig. 10 is a section on line 10—10 Fig. 7.

The construction of the cigar wrapping mechanism is not shown, but Figs. 1 and 2 show the relative arrangement of the means for respectively forming the wrappers, feeding the bands from a stack and advancing a row of cigars, together with transfer mechanism for assembling a wrapper, a band and a cigar in proper registration, and for delivering the same to a position

for engagement with the wrapping mechanism. As shown in Fig. 2, a row of cigars A is intermittently advanced in the direction indicated by the arrow to successively bring the foremost cigar

of the row beneath a bifurcated member B. This member is intermittently reciprocated between the position shown respectively in Fig. 1 and Fig.

2, and as will be hereinafter described, carries with it a cigar, a wrapper and a band to a position for engagement with the wrapping mecha-

nism (not shown). The wrapper is formed from a strip of suitable material such as "Cellophane", which is delivered from a supply roll C through the intermittent operation of feed rolls D to a position parallel to and at one side of the mem-

ber B. The forward end of the strip is engaged by a suction head E connecting with the member B by a laterally projecting arm F and which travels with said member between the positions

respectively shown in Figs. 1 and 2. Intermediate

these two positions there is arranged a table G which has its upper face normally at the level of the upper faces B and E but during movement of said members this table is lowered so as to

avoid interference therewith. H is a holder for a stack of bands arranged in inclined position in a plane parallel to the direction of movement of the members B and E and on the opposite side of the member E from the member B. I is a

rockable suction head which in one position is pressed against the lower end of the holder H to engage the lowermost band therein and in an-

other position extends horizontally in the plane of the upper faces of the members B and E.

To assemble the band, wrapper and cigar in proper registration, the foremost cigar of the row A is lifted by an elevator J into the space between the furcations of the member B where it is clamped by resilient spaced flanges K K'. The band is transferred from the suction head I to the table G which latter is also provided with a suction head and after the lowering of the table G the wrapper strip is fed over the table and 10 band by the rotation of feed rolls D and forward movement of the suction head E. While in this position the table G is raised to contact the band with the under side of the wrapper and at the same time shears L are operated to sever the 15 wrapper from the strip. Both wrapper and band are then transferred to the top of the member B to which they are held by suction.

For effecting the transfer of the band from the suction head I to the table G and also for transferring both band and wrapper from the table G to the member B, I have provided an oscillatory carrier M. This as shown in Fig. 4 is connected at its opposite ends to crank arms N which are periodically actuated in parallelism to move the 25 member M between the positions shown in full and dotted lines. Depending from the member M is a suction head O which in dotted position registers with the suction head I and in full position registers with the table G. There is also a 30 suction head P depending from the member M which in dotted position registers with the table G and suction head E and in full position registers with the member B. The suction head P is adapted for receiving wrappers of different 35 lengths corresponding to different lengths of cigars to be wrapped and to this end is formed of two L-shaped members P', P'', which together form a rectangle. Rows of suction ports P³ are arranged along these L-shaped members and together serve to hold the wrapper thereto. The 40 members P', P'' are adjustable transversely of the member M to enlarge or diminish the length of the suction head being slidable in grooves therein and are secured in adjusted position by clamps P⁴. Thus when properly adjusted the suction 45 head P will engage the wrapper on the table G and suction head E and after severing from the strip by operation of the shears L will transfer the wrapper to the member B to which it is held by suction ports B'.

As thus far described the member M functions to transfer the band from the suction head I to the table G and to transfer the wrapper from the table G and suction head E to the member B. This would not, however, transfer the band with 55 the wrapper inasmuch as the wrapper would close the ports of the suction head P so as to render them ineffective for lifting the band. I have therefore provided auxiliary means on the member M which will carry the band as well as the 60 wrapper into engagement with the member B, the construction being as follows:

Q is a head secured to the member M intermediate the members P', P'' which latter are recessed or cut away at P⁵ to receive said head. At 65 opposite ends of the head Q are needles Q', Q'' which when the head is placed against the table G with the wrapper and band lying thereon will penetrate both wrapper and band. Thus when the member M is lifted from the table G, the 70 needles Q', Q'' will carry the band with the wrapper to deposit both upon the member B, where both will be held by the suction ports B', B''.

From the description above it will be understood that in each cycle of operation a cigar will 75 be lifted by the elevator J into engagement with

the clamping members K and K', a band will be removed from the stack by the suction head I and will be transferred from said suction head to the table G. The wrapper strip will be advanced over the table G which is lowered to avoid interference. The wrapper will be severed from the strip and a wrapper and a band will be transferred from the table G and suction head E to the member B into a position for proper registration with the cigar. All of these, cigar, band and wrapper will then be transferred by the reciprocation of the member B to the position shown in full lines in Fig. 2, and in dotted lines, Fig. 7, where an elevator R will remove them from the member B into engagement with the wrapping mechanism (not shown). The various parts of this mechanism are properly timed with each other and with the wrapping mechanism by suitable connections (not shown). However, as indicated in Fig. 4, the raising and lowering of the table G is controlled by a cam S, lever S' and lifting rod S². The crank arms N are intermittently swung through a half revolution by the operation of gear wheels T, gear segments T', rock shaft T², rock arm T³ and other mechanism (not shown). The member B is reciprocated by a link N² and lever N' and the rockable suction head I is actuated by a gear segment V, rack bar V' and eccentric V².

To permit the needles Q', Q'' to penetrate the 30 wrapper and band while supported on the table G, the latter is provided with recesses G' which register with said needles and provide clearance therefor. As it is necessary to adjust the position of band relative to the wrapper for use on cigars 35 of different lengths, these recesses G' are preferably in the form of slots extending transversely of the table G so that in any position of adjustment of the head Q clearance is provided for the needles. The member B is also cut away as 40 indicated at B² to provide clearance for the projecting portions of the needles when the wrapper and band are deposited on said member. It will be understood that the suction to the various 45 suction heads is controlled by suitable means (not shown) so that suction is relieved from one head prior to the transfer therefrom of the wrapper or band by another head.

The member B which forms the carrier for 50 wrapper, band and cigar is preferably of the following construction: The cigars in the row A are fed into registration with the member B by a chain feed A' and the foremost cigar is arrested in the position of registration by a stop K² depending from the resilient flange K. The position of this stop may be adjusted for cigars of 55 different diameter so as to arrest the foremost cigar in the central plane of the bifurcated member B. This adjustment means comprises a flange K³ which is slotted and secured by a clamping bolt K⁴ passing through said slot. The resilient flange K' is carried by a member K⁵ which 60 passes over the cigars in the row and is then return bent and is adjustably secured in position by a clamping screw K⁶. This member K⁵ in conjunction with a hinged table K⁷ below the cigars and which is intermittently raised, forms a clamp for holding all of the cigars in the row 65 from further advancement during the interval in which the foremost cigar is raised by the elevator J. The member B is slideable on guide rods B³ and as before stated, is actuated by a reciprocating lever N' and link N². Between the furcations of this member B are the resilient flanges K and K' which extend parallel to the guide rods B³. 70

beyond the position of the elevator R, being attached at their outer ends to rock arms W and W' pivoted on pins W² and having bell crank arms W³ connected to each other by a pin W⁴ on the one engaging a slotted bearing on the other. A spring W⁵ places a resilient tension on these arms to move the strips K and K' towards each other. X is a bearing for engaging the end of the cigar having a shank X' which is adjustably secured in a depending lug X² on the member B arranged between the resilient strips K and K'. The arrangement is such that when the foremost cigar of the row A is raised by the elevator J it will pass between the resilient strips K and K' which are so adjusted as to receive therebetween a cigar of the series which is largest in diameter. In other words, cigars intended to be of the same size will vary more or less in diameter and therefore the strips K and K' are adjusted wide enough apart to receive the largest variation. While still supported by the elevator J the member B is moved by the lever N' and link N² and the bearing X engaging the end of the cigar will move it longitudinally between these resilient strips. The latter are bent inward towards each other as indicated at K⁸ so that a cigar of minimum diameter will come in contact with the two stops which will hold it in position centrally of the bifurcated member B during movement into registration with the wrapping mechanism. For cigars larger in diameter than the minimum the strips K and K' will be pressed apart, this being permitted by the rockable levers W, W', the bell crank arms W³ and the spring W⁵. Thus the construction is such that cigars of any diameter can be transferred by the carrier B and will be held by the strips K and K' centrally between the furcations of this carrier so as to be centralized with the wrapper and band.

40 What I claim as my invention is:

1. In a cigar wrapping machine, the combination of a plurality of mechanisms for respectively delivering individually at separate locations a cigar, a wrapper and a band, means for transferring a band from its delivered position into a position for registration with the wrapper in its delivered position, means for transferring the registered band and wrapper laterally thereof and delivering the same unattached to each other in registration with the cigar in its delivered position, and means for transferring the registered cigar, wrapper and band in a direction parallel to the longitudinal axis of the cigar into registration with the wrapping mechanism.

55 2. In a cigar wrapping machine, the combination of a plurality of mechanisms for respectively delivering individually at separate locations a cigar, a wrapper and a band, a reciprocating transfer carrier into engagement with which said cigar is delivered and which reciprocates in a direction parallel to the longitudinal axis of said cigar, means for transferring a band from its delivered position into a position for registration with a wrapper in its delivered position, means for transferring the registered band and wrapper laterally thereof and delivering the same unattached to each other to said transfer carrier in registration with the cigar in engagement therewith, means on said transfer carrier for retaining said cigar, band and wrapper in registration during the reciprocating movement of the carrier, and means for disengaging said cigar, band and wrapper from said carrier to deliver the same to the wrapping mechanism.

70 3. In a cigar wrapping machine, the combina-

tion of a plurality of mechanisms for respectively delivering individually at separate locations a cigar, a wrapper and a band, a reciprocating transfer carrier bifurcated to receive the delivered cigar between the furcations thereof, means for transferring a band from the delivered position into a position for registration with the wrapper in its delivered position, means for transferring the registered band and wrapper laterally thereof and delivering the same unattached to each other on top of said transfer carrier in registration with the cigar therein, the furcations of said carrier being provided with suction ports for retaining the wrapper and band in engagement therewith during reciprocation of the carrier, and an elevator located at the opposite end of movement of said carrier for disengaging said cigar therefrom and carrying with it the band and wrapper to deliver the same to the wrapping mechanism.

4. In a cigar wrapping machine, the combination of a plurality of mechanisms for respectively delivering individually in separate locations a cigar, a wrapper and a band, means for transferring a band from its delivered position into a position for registration with the wrapper in its delivered position, a table for receiving the band from said transfer means and for depressing the same out of the path of the wrapper during the delivery thereof, a suction head for engaging the wrapper above the band supported on said table and for transferring the same into registration with the cigar in its delivered position and one or more needles on said suction head for penetrating both wrapper and band whereby both are carried together and are delivered unattached to each other in registration with the cigar.

5. In a cigar wrapping machine, the combination of a plurality of mechanisms for respectively delivering individually in separate locations a cigar, a wrapper and a band, a bifurcated reciprocating carrier located to receive between the furcations thereof the cigar in its delivered position, means for transferring a band from its delivered position into a position for registration with the wrapper in its delivered position, a table on which said band is received, means for depressing said table during delivery of the wrapper thereabove and for then raising it to press the band against the wrapper, a suction head for engaging the wrapper above said band while supported on said table and for transferring and depositing the same on said reciprocating carrier in registration with the cigar therein, and one or more needles on said suction head for penetrating both the wrapper and the band while on said table and adapted to carry the latter with the former into engagement with said reciprocating carrier, suction means in the furcations of said carrier for retaining the band and wrapper thereon during disengagement of said suction head and needles therefrom and during movement of said carrier, and means located at the opposite end of movement of said reciprocating carrier for disengaging the cigar, band and wrapper therefrom and for delivering the same to the wrapping mechanism.

6. In a cigar wrapping mechanism, the combination of a plurality of mechanisms for respectively delivering individually in separate locations a cigar, a wrapper and a band, a reciprocating carrier for transferring a band from its delivered position into a position for registration with a wrapper in its delivered position and for simultaneously transferring a wrapper from

its delivered position into a position for registration with a cigar in its delivered position, a table for receiving the band from said carrier, means for depressing said table during delivery of the wrapper above said band and for then raising said table to press the band against the under side of said wrapper and one or more needles on said transfer carrier for penetrating both the wrapper and band while supported on said table and for retaining both in registration during transfer and delivery in registration with said cigar.

7. In a cigar wrapping machine, a transfer carrier for a cigar, a wrapper and a band held in proper registration with each other comprising a bifurcated member reciprocating in a direction parallel to the longitudinal axis of the cigar and having suction ports in the upper face of the furcations thereof, means for delivering a wrapper and a band to extend across above said furcations and to be held thereon by the suction of said ports, means for elevating a cigar between the furcations, resilient strips arranged between the furcations and extending along the path of reciprocation of said member, said strips being adjustably spaced to receive the elevated cigar therebetween, and a bearing on said bifurcated member depending therefrom between said resilient strips to engage the end 30 of the cigar and to propel the same with said carrier while being guided by said strips.

8. In a cigar wrapping machine, the combination with means for advancing a row of cigars, of a reciprocating carrier movable in a direction transverse to the advancement of said cigars and above the plane thereof, said carrier comprising a bifurcated member having suction ports in the upper face of the furcations thereof for holding thereon a wrapper and a band, spaced resilient guide strips arranged between the furcations of said carrier and extending throughout the path of movement thereof, said strips being adjustable to receive therebetween cigars of different thickness and one of said strips having a stop depending therefrom for arresting the foremost cigar of said advancing series in registration with the space between said strips, and means engaging the opposite ends of said strips for resiliently pressing the same towards each other to adjust to cigars varying in thickness and to hold the same central with respect to said carrier, means for elevating the foremost cigar of said advancing series between said strips, and a bearing on said carrier depending therefrom between said strips to engage the end of the cigar and to propel the same between said strips into a position for registration with the wrapping mechanism.

9. In a cigar wrapping machine, the combination with means for advancing a row of cigars, of a reciprocating carrier movable in a direction transverse to the advancement of said cigars and in a plane above the same, said carrier comprising a bifurcated member and means for engaging a wrapper and a band with the furcations thereof, a pair of guide strips arranged between the furcations of said carrier and extending throughout the length of travel thereof, one of said strips having a depending portion forming a stop for arresting the advancement of the cigars in said series, means for adjusting the ends of the strips adjacent to said row of cigars for spacing the same to receive therebetween a cigar of a predetermined thickness, an elevator for raising the foremost cigar of the series in between said strips, a bearing on said reciprocating carrier depending therefrom between said strips to engage the end of the cigar and to propel it with the carrier to a position of registration with the wrapping mechanism, a pair of rock arms for supporting the opposite ends of said strips, said rock arms being interconnected to compel equal movement thereof on opposite sides of the center of said carrier, and resilient means for moving said rock arms towards each other to thereby resiliently press said stops against the cigar propelled therebetween and to adjust the same to cigars of varying thickness. 30

10. In a cigar wrapping machine, the combination of a plurality of mechanisms for respectively delivering individually at separate locations a cigar, a wrapper and a band, means for transferring one of these elements from its delivered position into predetermined registration with a second element in its delivered position and for delivering the two registered elements into predetermined registration with a third element in its delivered position, the band being positioned between the wrapper and the cigar in predetermined relation thereto. 35

11. In a cigar wrapping machine, the combination of a plurality of mechanisms for respectively delivering individually and at separate locations a cigar, a wrapper and a band, means for transferring one of these elements from its delivered position into predetermined registration with a second element in its delivered position, means for transferring the two registered elements into predetermined registration with a third element in its delivered position the band being positioned between the wrapper and cigar in predetermined relation thereto, and means for delivering the three registered elements to the 50 wrapping mechanism. 55

ALFRED W. KATH.
